BERTRAN LAURITSEN, OF MARVIN, SOUTH DAKOTA.

JAR OR CAN HOLDER.

Application filed August 19, 1922. Serial No. 583,057.

To all whom it may concern:

Be it known that I, BERTRAN LAURITSEN, a citizen of the United States, residing at Marvin, in the county of Grant and State 5 of South Dakota, have invented a new and useful Improvement in Jar or Can Holders, of which the following is a specification.

This invention relates to jar or can holders.

10 The object is to provide a simple, cheaply manufactured and easily operated device especially adapted for domestic use, whereby a fruit jar or can may be rigidly held in position upon a table or other support, 15 while both hands of the operator may be employed in applying the screw cap in position thereon or in removing the same in the usual manner.

Another object is to provide a device of 20 this character having cushioned means for frictionally holding the jar or can from turning, which, when glass jars are being operated on, serve to hold the same with sufficient force to screw or unscrew the cap 25 ordinarily, but which will permit turning of the jar before the breaking point is reached when more power is applied to the cap than the jar will stand.

A further object is to provide a holding 30 means for jars and the like which may be adjusted to receive jars of different sizes, and which may be easily and quickly released from the holder when the operation 35 of applying or removing the cap is finished by the simple swinging of a lever.

A full and complete understanding of the invention may be obtained from a consideration 40 of the following detailed description, taken in connection with the accompanying drawing forming a part of this specification, it being understood that while the drawing shows a practical form of the invention, the latter is not to be confined to strict conformity with the showing thereof 45 but may be changed or modified, so long as such changes or modifications mark no material departure from the salient features of the invention, as specifically pointed out in the appended claims.

50 In the drawing, in which similar reference characters designate corresponding parts throughout the several figures:

Figure 1 is a perspective view of the jar or can holder in applied position on the edge 55 of a table and shown holding a jar;

Figure 2 is a longitudinal sectional view of the device, the jar being omitted; and

Figure 3 is a top plan view of the device, the cover plate being removed.

In canning or preserving fruits, vegetables, etc., it is generally difficult to hold the jar with sufficient power to apply the screw cap tight enough to properly seal the same, and this is doubly so when the jar is filled with hot contents and the cap must be applied immediately. Difficulty is also encountered in removing caps from jars when it is desired to use the contents thereof, for the reason that the glass jar slips through the fingers gripping the same especially when a mechanical cap remover is used.

The present invention is designed to overcome these difficulties by providing means for resiliently holding the jar or can to prevent breaking the same and yet with sufficient force to remove the average cap.

In the drawing there is illustrated the preferred form of the device which comprises an elongated body member 1 formed preferably of some metal, such as cast iron, the said body member being rectangular in cross section, and provided in its upper face with a longitudinally disposed channel 2 extending from end to end of the same. The channel is formed at one end with a slightly depressed, rounded bottom 3, and at the other end terminates in an inclined wall 4 connecting with a short horizontal wall which terminates short of the end of the body member in a vertically disposed wall 5, thus forming, in effect, spaced side plates at the end of the body member.

At the center of the body member the side walls of the channel 2 are somewhat closer together than at the opposite ends of the same, to form guiding or bearing faces 6 for a purpose to be explained, and the lower face of the said body member is provided with a depending arm 7 located at the center of the same, with its outer face flush with the side wall of the body member and its inner face arranged at an angle to the longitudinal axis of the body, as indicated in dotted lines at 8 in Figure 3. The lower end of the arm 7 carries a horizontally disposed clamping plate 9 arranged at an angle to the body member, and provided with a threaded aperture for the reception of a clamping screw 10, which is adapted to engage the underside of a table 11, or other

support, as clearly shown in Figures 1 and 2 of the drawing. The angular disposed wall 8 positions the body member at an angle relatively to the edge of the table top 11, 5 so that the end of the channel having the depressed, rounded bottom 3 is located over the same, while the other end having the spaced side plates is positioned outside of said edge. The bottom of the body member 10 is also provided with a bearing surface 7^a, located directly over the angularly disposed clamping plate 9, and the screw 10 is preferably provided with a swivelled disc or plate 10^a to allow the screw to hold tightly 15 without damaging the underside of the table top in a well known manner.

Mounted in the channel 2 is a reciprocating plunger rod 12 which is adapted to freely slide longitudinally between the bearing faces 6—6, and said rod is provided with an enlarged end 13 fitting the rounded, depressed bottom 3 of the channel and extending beyond the end of the same, where it is provided with a flared head 14 having its 25 outer end face 15 curved to fit a jar and provided with a layer of felt 16 or other padding material.

At the opposite or inner end, the plunger rod 12 is provided with an eye 17 normally 30 located adjacent to the upper end of the inclined wall 4, and to this eye is connected the inner end of a wire bail or link 18, the sides of the said eye 17 being reduced so as to allow ample space between the side 35 walls of the channel for the said link to freely slide longitudinally therebetween, as clearly shown in Figure 3. The outer end of the link is connected to the short end 19 of a bell crank lever 20, whose other and longer 40 arm is formed into a thumb piece 21 adapted to be swung about the pivot 22 traversing the lever at the angle of the same, and the aforesaid side plates at the end of the body member. When the lever 20 is released 45 to allow the plunger to project the enlarged end 13 beyond the adjacent end of the body member, the thumb piece extends outwardly from the end of the body member, and when the lever is in the other position, the inner 50 edge of the thumb piece strikes against the vertical wall 5 in the body member, and the plunger is locked in its innermost position, with the link 18 resting across the pivot pin 22 against the resistance of an expansion 55 spring 23, which is in surrounding relation to the portion 12 of the plunger, and abutting at its ends against the inner end of the enlarged portion 13 thereof and the inner end of the depressed portion 3 of the channel. When the locking lever 20 is 60 swung to the position shown in Figure 1, the said spring 23 forces the jar engaging head 14 outwardly to frictionally engage the side of a jar 24, as in Figure 1, after 65 the same has been placed within the encir-

eling, coacting holding band 25 formed preferably of a thin, flexible steel ribbon, shaped into a loop and having one end permanently attached to the adjacent end of the body member, as by a rivet 26. The inner face of the band 25 is provided with a facing strip 27 of felt of similar material for engaging the jar 24, in opposition to the strip 16 of the plunger head 14, and the other or free end of the strip 25 is extended along the opposite side of the body member, and is passed through a vertically disposed keeper loop 28, and provided at its terminal with an eye 29, which is adapted to be engaged with one of a series of hooks 30, 31 and 32 so positioned 80 on the side of the body member as to enable the loop portion of the clamping band 25 to embrace a pint jar, a quart jar or a two-quart jar respectively, as will be readily understood.

A cover plate 33 held by screws 34 is attached to the top of the body member across the channel and extends to the inclined wall 4, thus serving to hold the plunger and spring in position, ample space being thus 90 provided for the swinging movement of the link 18.

With the eye 29 of the clamping band engaged with the proper hook to fit the size of the jar to be operated on, and the plunger retracted into the body member and locked therein against the expansive force of the spring 23, with the thumb piece of the bell crank lever bearing against the wall 5, the jar 24 is then placed on the surface of the 100 table 11 and within the said band. By merely forcing the thumb piece rearwardly and upwardly, the spring 23 will cause the head 14 to engage the jar with sufficient force in opposition to the band 25, to enable 105 the cap 24 to be either screwed on or off the mouth of the jar.

From the foregoing it will be seen that a simple, cheaply manufactured, and easily and quickly operated cap removing device 110 has been provided, which may be clamped in position on the overhanging edge of a kitchen table or other support, and that the same will act to hold jars or cans with sufficient force for the purpose without danger 115 of breaking the same.

What is claimed is:—

1. A jar or can holding device comprising an elongated base member, means for clamping the same to a support, said base member having a channel therein, a plunger movable in the channel and extending beyond one end of the base member, a padded head carried by one end of the plunger, a lever connected to the other end of the plunger at the end of the base member, a flexible padded band secured at one end to the base member, and means for adjustably connecting the other end to the base member.
2. A jar or can holding device comprising 130

an elongated base member adapted to be clamped to the edge of a table and having a longitudinally disposed channel therein, a plunger arranged in the channel and extending beyond one end of the base member, said end having a flared, curved and padded head to engage a jar or can, a flexible, padded metallic band secured at one end to the end of the base member adjacent to the plunger head and adapted to surround the jar or can, the other end being adjustably secured to the opposite side of the base member, a hand actuated bell crank lever pivotally mounted in the opposite end of the

base member, one end of the said lever normally extending from the end thereof and formed into a thumb piece, the short end of the lever being substantially in a line with the channel, a link connecting the said short end with the plunger, and a coiled spring surrounding the latter in the channel to force the plunger head outwardly in opposition to said band when the lever is released.

In testimony, that I claim the foregoing as my own, I have hereto affixed my signature.

BERTRAN LAURITSEN.
